GARMENT HANGER

Walter H. Boal, South Bend, Ind.
(Redbud Trail, R.D. 2, Box 364A, Berrien Springs, Mich.)

Filed Mar. 9, 1959, Ser. No. 798,011

1 Claim. (Cl. 53—241)

This invention relates to garment hangers and more particularly to an aid device for covering garments or wearing apparel at home, stores, shops and while traveling with a bag-type cover.

This device makes it easy to remove a garment or add one or more garments to the hanger and cover with same bag while bag is up out of the way. When the garments are ready to cover, it is merely necessary to pull the bag down in place.

One important object of this invention is to provide a novel portable garment hanger so that the user shall be able to remove the garment from the bag that is received from the cleaners without destroying the bag or cover.

Another object of the invention is to provide a novel form of spring actuated portable garment hanger and cover bag applying device.

A further object is to be able to hang the device on the top of any door without hindering the operation of the door in any way and can be readily used at any time and at any place.

These and other objects of the invention will be more manifest from the following specification and drawings and more particularly set forth in the claim.

In the drawings:

Figure 1 is a sectional view in elevation of the garment hanger and bag applying device;

Figure 2 is a front view of the apparatus shown in Figure 1, and illustrating two positions of the hanger operation;

Figure 3 is a modified sectional view of the spring device shown in Figure 1;

Figure 4 is a top plan fragmentary view of the device shown in Figure 3; and

Figure 5 includes front and elevation views of the web stop device.

The reference numeral 1 denotes a standard door within a house, hotel or building. Referring to Figures 1, 2, 3 and 4, a stem 2 is inserted into a hole 16 in the casing 3 and is retained there by a spring 4 and a washer 5. This stem 2 is, therefore, spring-loaded and the stem 2 may be adjusted to fit any size door or ledge or furniture, such as the case may demand. The washer 5 has a given slot 18 in it to accept the stem 2 and locate and/or guide the stem 2 within the casing 3. After the stem 2 has been inserted into the casing 3, the spring 4 is threaded onto the stem 2 and is followed by the washer 5, then the end of the stem 2 is bent in a prescribed manner which makes possible the spring action on the stem 2.

The casing 3 is provided with a cover 12 which is to be cemented in place on the casing 3. But before this is done, the coiled spring metal strap 6 must be pre-assem-

2

bled and installed into the casing 3. The clip or end 9 is first fastened to the strap 6 by the means of a rivet 8. The strap 6 is then pressed into slot 18 which is in a base 7 of the casing 3 and then coiled and fitted into a slot 17 of the casing 3. The first position shown in Figures 1, 2, 3 and 4 is the position the strap 6 will occupy while not in use. The second position shown in Figures 1, 2, 3 and 4 is the position the strap will occupy while in use. In this position, a bag-type cover 10 is threaded onto the strap 6 and held in place by the clip part of the end 9. After a bag-type cover 10 has been threaded over the strap 6, one or several garments can be hung on the end 9 by means of hanger or hangers 11. After the desired number of garments are hanging on the end 9, the bag-type cover 10 may be released from the clip portion of the end 9 and the cover 10 pulled down over the garments.

Referring now to Figures 3 and 4, the cavity for the spring 4, stem 2 and washer 5 has been rotated 45° and the casing 3 modified to accept the position of said cavity. The parts are the same and the assembly is also the same as described beforehand with the exception of the end 14. It is modified to suit this particular assembly and is to be used only as shown in Figures 3 and 4.

Referring now to Figure 5, it shows only a front plan view and a side view of the end 14 used in Figures 3 and 4 with the rivet 8 in position for assembling the end 14 into the strap 6.

This device will be easy to transport and can be used for vacation or business trips and is durable and easy to manufacture. It also can be easily operated by either man, woman, or child.

The primary function of this device is to place a bag-type cover over garments thus: first extract the strap 35 from the case, thread it through a bag-type cover, hang the garment to be covered by inserting the hooked hangers through the eye at the end of the strap, pull the cover down over the garments, remove them from the eye on the strap and when the strap is released, it will retract 40 back into the case out of the way.

Having thus described a combination garment hanger and bag covering device constructed in accordance with the present invention, various changes may be made therein without departing from the invention as set forth 45 in the claim.

What is claimed is:

In a portable garment hanger device, the combination of a relatively small enclosed casing, yieldable means including a horizontally movable stem member, means for attaching the stem to said casing, means at the opposite extremity of the stem for freely attaching the casing to a support, an axle mounted in the casing, a coil spring strap member having one end secured to the axle and the other end projecting from the casing and a garment hanger hook connected to the projecting end.
